DOORCHECK

Earl S. Burdick, Milwaukie, and Charles R. Thomson, Portland, Oreg., assignors to Klosterman Inc., Portland, Oreg.

Application February 27, 1932. Serial No. 595,580

1 Claim. (Cl. 16—53)

This invention relates generally to door checks, and particularly to an improved form of spring-actuated check having a hydraulic controlling device.

5 The main object of this invention is the provision of an improved form of door check in which the retarding action of the hydraulic element can be adjustably dispensed with for the end of the closing operation.

10 The second object is to so construct the check as to simplify its construction and to remove from the exterior thereof as many working parts as possible.

These, and other objects, will become more apparent from the specification following as illustrated in the accompanying drawings, in which:

Fig. 1 is an elevation of the device showing the door in an open position.

Fig. 2 is a plan showing the parts in a closed position in full lines and in partial and fully opened position in dotted lines.

Fig. 3 is a section taken along the line 3—3 in Fig. 2.

Fig. 4 is a section taken along the line 4—4 in Fig. 6.

Fig. 5 is a section taken along the line 5—5 in Fig. 6.

Fig. 6 is a section taken along the line 6—6 in Fig. 1 showing the parts in a closed door position.

Fig. 7 is a view similar to Fig. 6 showing the parts in a door-closing position.

Fig. 8 is a section taken along the line 8—8 in Fig. 7.

Fig. 9 is a perspective view of the valve release rod.

Fig. 10 is a perspective view of the ball retainer.

Fig. 11 is a development of the cam surface.

Fig. 12 is a sectional view through an alternative form of the device.

Similar numbers of reference refer to similar parts throughout the several views.

Referring in detail to the drawings, there is shown a door frame 12 on which is swung the ordinary door 13. To the casing 14 of the frame 12 is attached a screen door 15 by means of the hinges 16.

Referring particularly to this invention same will be seen to consist of a base 17 having an extending flange 18 by means of which it may be secured to the door frame 12 by the screws 19. The portion 20 of the base 17 is cylindrical and in its inner surface 21 are formed the cam grooves 22 and 23, making it possible to use it as a right or left hand check.

Within the portion 20 is a rotatable cam 24 which is mounted upon a tubular stem 25 whose upper end is threaded to receive the adjusting screw 26, and whose lower end is threaded to receive a tubular plug 27. Between the plug 27 and the screw 26 and within the stem 25 is formed a valve seat 28 upon which can rest a ball check 29, which is urged toward the seat 28 by a spring 30 whose compression is controlled by the setting of the screw 26.

Within the tubular plug 27 is a valve release stem 31 having a cross shape stop 32 between the ends thereof, which stop is capable of a limited movement between the valve seat 28 and the upper end of the plug 27. The stem 25 is provided with outlet ports 33 directly above the valve seat 28.

The lower end of the stem 25 is provided with a shoulder 34 against which rests a piston 35. The piston 35 has a recess 36 on the upper side 75 thereof which receives the combined compression and torsion spring 37, whose upper end reacts against the top 38 of the recess 39 on the under side of the base 17. The piston 35 and the base 17 are provided with holes 40 to receive the spring ends 41. The piston 35 is also provided with openings 42 capable of being closed by the ball check 43 which is confined within the enlarged opening 44 by the ball retainer 45. The ball retainer 45 is held in position by means of the lock nut 46 on the tubular plug 27. The ball retainer 45 is provided with upturned arms 47 which project into the openings 44.

Upon the portion 20 is mounted a head 49 which is rotatable as well as slidable on the portion 90 20. Within the head 49 are the lugs 50 which engage the slot 51 formed across the diameter of the cam 24. A nut 52 is rotatably mounted in the head 49 and receives the upper end of the screw 26. The head 53 of the nut 52 engages the top 95 face 54 of the head 49.

On the door 15 is secured an angle bracket 55 one side of which is provided with a slot 56 which receives the elongated pin 57, which in turn is mounted in the end 58 of the arm 59 10 which, in this instance, is shown as integral with the head 49. The arm 59 is curved to provide the desired amount of clearance when the door 15 is wide open.

Surrounding the piston 35 is a cylindrical shell 10 60 whose bottom end 61 is closed and whose upper end 62 is threaded into the recess 39 of the base 17. A suitable liquid 63 is placed within the shell 60.

The operation of the device is as follows: Assuming that the parts are attached to a door (as 11

shown in Fig. 2), and an effort is made to open the door, a rotating movement will be supplied to the head 49 through the arm 59, and through the lugs 50 this movement is imparted to the cam 24 causing an axially slideable movement thereof and a correspondingly increased load on the spring 37.

It is assumed that the device has been assembled with the cam 24 occupying the correct groove 10 22 or 23, depending upon whether the door is right hand or left hand. This movement which 15 raises the piston 35 within the cylindrical shell 60 causes oil to rush through the openings 42, unseating the ball checks 43 and offering only 20 a minimum amount of resistance to the opening of the door, the actual amount exceeding only slightly that required to compress the spring 37. When the door is released the spring 37 attempts to return the parts 25 to their original position, causing the piston 35 to descend, and also causing the liquid 63 to rush upwardly through the openings 42, carrying with it the balls 43, which close the door and prevent the further passage of liquid therethrough.

Oil is, however, passing through the opening within the valve seat 28, causing the ball 29 to be unseated under the control of the spring 30, whose compression has been regulated, as stated, by the screw 26. The oil which passes the ball 29 goes 30 out through the ports 33 to the top side of the piston 35. However, as the piston 35 descends, carrying with it the valve release stem 31, its lower end eventually strikes the bottom 61 causing a full release of the ball 29, entirely overcom- 35 ing the action of the spring 30 and permitting the final portion of the closing action of the door to be performed by the spring 37, with no further resistance than exists in the natural friction of the door or its operating parts.

40 In the form of the device shown in Fig. 12 the

construction is identical with the one thus far described, except that the spring 48 is not a torsion spring and acts only in compression, and the pitch of the cam 24 may need to be decreased since all of the closing action must be performed directly by the compression of the spring 48 against the cam 24.

Attention is drawn to the copending application of David E. Riggins, Serial Number 582,907, over which this device is an improvement.

We claim:

A door check comprising a base having a flange for securing same to a door frame, said base having an upright cylindrical shell depending therefrom, said shell being closed at its lowermost end, the upper portion of said base having a spirally grooved recess formed therein concentric with said shell, a cylindrical cam occupying said recess and having a portion thereof engaging said spiral groove, said cam being capable of a spiral movement with relation to said recess, a stem attached to said cam, a piston on the lower end of said stem including an adjustably tensioned check valve opening under downward movement of the piston and a second check valve opening 100 under upward movement of said piston, a torsion spring surrounding said stem between said base and piston, a head rotatably mounted on said base in slidable relation thereto having driving connections to said cam, a screw extending down through said head and threading into said stem, a spring between the lower end of said screw and said adjustable check valve, a nut rotatably mounted in said head for locking said screw and a means for unseating said adjustable 105 check valve near the end of the downward travel of said piston.
